CLAIM

The ornamental design for a window wreath hanger, as shown and described.

DESCRIPTION

FIG. 1 is a front perspective view of a window wreath hanger, showing our design;

FIG. 2 is a top plan view thereof;

FIG. 3 is a front elevation view thereof;

FIG. 4 is a right side elevation view thereof;

FIG. 5 is a left side elevation view thereof; and,

FIG. 6 is a rear elevation view thereof; and,

FIG. 7 is a bottom plan view thereof.
